UNITED STATES PATENT OFFICE.

JOHN SINKO, OF CHICAGO, ILLINOIS.

CIGAR-LIGHTER TIP.

Application filed April 16, 1928. Serial No. 270,208.

This invention relates to electric cigar lighters constituting a common accessory of automobiles and usually characterized structurally by the provision of a metallic tip member containing an insulated spiral of fine wire constituting the lighter element, the tip being mounted on one end of a circuit cord that is connected to a battery or other source of current either directly, or through a reel on which the cord is wound, when the lighter is not in use.

My present invention relates to an improved lighter tip, and more specifically to that type of lighter tip wherein the circuit is opened and closed by a manually operated switch in the tip itself. The main objects of the invention are, to provide a simplified and improved structure and arrangement of current conducting and insulating elements, including a manually operated normally opened switch within the holder tube of the tip; to provide a construction wherein the removable igniter carrying block shall be securely locked in the holder tube against accidental displacement; and, generally, to reduce the cost of manufacture and simplify and improve the construction of cigar lighter tips of the type specified.

An improved mechanical embodiment of the present invention is illustrated in the accompanying drawings, in which—

Fig. 1 is an axial vertical section through the assembled tip;

Fig. 2 is a horizontal section on the line 2—2 of Fig. 1;

Fig. 3 is a horizontal section on the line 3—3 of Fig. 1;

Fig. 4 is a perspective view of the upper portion of the holder tube;

Fig. 5 is a detail in side elevation of the outer insulating block that carries the ignition element;

Fig. 6 is a side elevational view of the inner insulating block and parts immediately associated therewith;

Fig. 7 is a perspective elevation of the ash guard;

Referring to the drawing, 10 designates the metal holder tube which is formed substantially mid-length thereof with an internal shoulder 11 and at its lower end with a hole 12 through which extends the usual cord 13 carrying the insulated circuit wires 14 and 15.

Within the lower portion of the holder tube is an inner insulating block 16 that is formed

on its upper end with an annular flange 17 seating on the shoulder 11, and is encircled by a brass ferrule or contact shell 18. The block 16 has a central socket or well 19, in the bottom wall of which is mounted an eyelet 20 to the lower end of which is soldered the circuit wire 14. The eyelet 20 serves to attach to the lower end of the block 16 a leaf spring switch 21 and an insulating strip 22 lying parallel with the switch 21 and on the outer side of the latter. The switch and insulating strips 21 and 22 extend upwardly through a vertical groove 23 in the block 16, as clearly shown in Fig. 3, both of the members 21 and 22 lying inside a flattened portion 18' (Fig. 3) of the ferrule 18, and extending some distance above the top of the block 16.

Fitted within the socket 19 is a metal contact sleeve 24 closed at its lower end and at its upper end formed with an annular shoulder 24' resting upon the top of the block 16. Seated within the sleeve 24 is a thrust spring 25, the upper end of which serves to force upwardly a contact plunger 26, the latter being confined against escape by an annular lip 27 on the sleeve 24 engaged with an annular shoulder 28 on the plunger 26. The plunger 26 is formed with a concave seat 26' on its upper end for a purpose hereinafter described.

29 designates an outer insulating block, the lower portion of which is enclosed by a brass contact sleeve 30 formed in its bottom with a central aperture through which projects a conical lug 29' on the lower end of the block 29. In the upper portion of the holder tube 10 are formed a pair of diametrically opposed bayonet slots 31 (Fig. 4), and these slots are engaged by outwardly pressed lugs 32 (Fig. 5) formed on the shell 30. The block 29 is formed with a central hole 33, through which extends a wire 34 that is soldered at its lower end to a contact tip 35 that is seated on the lug 29' and is formed with a convex lower face normally fitting the seat 26' in the plunger 26. The wire 34 constitutes an extension of the inner end of a spiral igniter coil 36 that is seated in a shallow recess 37 in the face of the insulating block 29. An extension 38 of the outer end of the igniter coil 36 passes down through an eccentric hole 39 in the block 29 and at its lower end is soldered to the bottom wall of the shell 30.

A hole 40 is formed through the upper portion of the holder tube 10 (see Fig. 4), and through this hole extends the shank 41 of a

push-button, said button being formed on its inner end with an enlarged tapered head 41' against which the spring switch 21 and insulating strip 22 exert an outward thrust, holding the push-button head 41' in contact with the inner edge of the hole 40.

Telescoping over the upper end of the holder tube 10 is the usual ash guard 42 formed with an indented lug 43 that interlocks with a bayonet slot 44 (Fig. 7) in the upper portion of the holder tube 10. To prevent turning of the shell 30 on the block 29, the latter is formed in its side with a depression 29a (Fig. 2) receiving an indentation 15 30a in the shell 30.

When the push-button 41 is pressed in to carry the switch 21 into contact with the upper portion of the contact sleeve 24, the course of the current is as follows: wire 14, eyelet 20 20, switch 21, contact sleeve 24, plunger 26, contact tip 35, wire 34, igniter coil 36, wire 38, shell 30, holder tube 10, shell 18 and wire 15. The circuit is normally open between the switch 21 and the contact sleeve 24, as shown 25 in Fig. 1.

The function of the spring 25 is three-fold. It exerts a constant upward thrust through the plunger 26 on the contact tip 35 and through the latter to the outer insulating 30 block 29, which maintains the locking lugs 32 of the latter securely interlocked with the bayonet joints 31 of the holder tube. It also insures a perfect electrical contact between the plunger 26 and the contact tip 35. And it 35 also exerts a downward thrust on the insulating block 16, maintaining the latter on its seat 11 and insuring the proper cooperative relation of the spring switch 21 and the push-button 41. The spring 25 is always under 40 tension, and its action is not in any way related to the making and breaking of the circuit.

With the structure shown, the parts are very easily assembled and disassembled. In 45 assembling, the holder tube is first passed over the upper end of the cord 13 and the wires 14 and 15 are soldered to the eyelet 20 and shell 18, respectively. The insulating block 16 is then drawn down into the holder tube until arrested by the engagement of its shoulder 17 with the seat 11, the parts carried by the insulation block having been previously assembled thereon. Prior to drawing the insulation block 16 to its seat, push-button 41 is entered through the hole 40 from 50 the inside, and is held in working position by the spring switch 21 when the latter is in place. The upper insulation block 29 equipped with the igniter wires and coil is 55 then inserted into the upper end of the holder tube 10 and pressed downwardly, compressing the spring 25, and then turned to carry its lugs 32 into engagement with the bayonet slots 31. The ash guard is then inserted over 60 the end of the holder tube 10 and given a 65

slight turn to interlock its lug 43 with the bayonet joint 44, and the tip is then fully assembled and ready for use. By the simple reverse of the above described operations, the parts may be disassembled for examination 70 and repair whenever necessary.

Within the recess 19 below the contact sleeve 24 I have shown an insulating disc 45 to insure against any possible short circuit between the eyelet 20 and the sleeve 24. The 75 lower end of the ash guard 42 is notched as shown at 46 to straddle the shank of the push-button 41.

The described structure provides a very simple, comparatively inexpensive, and efficient manually operable cigar lighter tip, in which the upper and lower insulation blocks 29 and 16 and the parts associated therewith are constantly maintained in proper working relation without any rattle or lost motion or accidental separation of current-conducting parts:

I claim—

1. In a lighter tip of the type described, the combination of a holder tube, a recessed inner insulation block fitted into said tube, an insulated spring switch secured to and extending outwardly beyond said block, a push-button mounted in the wall of said holder tube and thrust outwardly by said switch, a plunger guide mounted in the recess of said block having a portion thereof adapted to make and break contact with said switch, a contact plunger slidable in said guide, a spring urging said plunger outwardly of said guide, an outer insulation block in said holder tube detachably interlocked with the latter, a metal contact tip on the inner end of said outer block pressed against by said plunger, an igniter element on said outer block electrically connected at one end to said contact tip and at its other end to said holder tube, and circuit wires respectively electrically connected to said switch and to said holder tube.

2. In a lighter tip of the type described, the combination of a holder tube, a recessed inner insulation block fitted into said tube, an insulated spring switch attached to the inner end of said block and extending outwardly beyond the latter, a push-button mounted in the wall of said holder tube and thrust outwardly by said switch, a shouldered plunger guide mounted in the recess of said block, the shoulder whereof is adapted to make and break contact with said switch, a contact plunger slidable in said guide, a thrust spring in said guide urging said plunger outwardly, an outer insulation block in said holder tube detachably interlocked with the latter, a metal contact tip on the inner end of said outer block pressed against by the outer end of said plunger, an igniter coil on the outer face of said outer block electrically connected at one end to said contact tip and at its other end to said holder tube,

and circuit wires respectively electrically connected to the inner end of said switch and to said holder tube.

3. In a lighter tip of the type described, 5 the combination of a holder tube, a centrally recessed inner insulation block carrying a metal contact shell fitted into said tube, an insulated spring switch attached to and extending outwardly beyond said block, a push-button mounted in the wall of said holder tube and thrust outwardly by said switch, a plunger guide mounted in and projecting beyond the recess of said block, the projecting portion of said guide cooperating with said 10 switch to make and break the circuit, a contact plunger slidable in said guide, a spring in said guide urging said plunger outwardly, an outer insulation block carrying a metal contact shell in and detachably interlocked 15 with said holder tube, a metal contact tip on the inner end of said outer block pressed against by the outer end of said plunger, an igniter element on said outer block electrically connected at one end to said contact tip and 20 at its other end to said last-named contact shell, and circuit wires respectively electrically connected to said switch and to said first-named contact shell.

4. In a lighter tip of the type described, 25 30 the combination of a holder tube formed with an internal shoulder, an inner insulation

block formed with a shoulder supported on the shoulder of said tube, a central recess, and a longitudinal groove, a metal contact shell surrounding said block and fitting the 35 wall of said tube, an insulated spring switch attached to the inner end of said block and extending through said groove outwardly beyond said block, a push-button mounted in the wall of said holder tube and thrust outwardly by said switch, a plunger guide sleeve mounted in and projecting beyond the recess of said block, the projecting portion of said 40 guide sleeve being enlarged diametrically and cooperating with said switch to make and break the circuit, a contact plunger slidable in said guide sleeve, a coil spring in said guide sleeve urging said plunger outwardly, an outer insulation block carrying a metal contact shell in and detachably interlocked 45 with said holder tube, a metal contact tip on the inner end of said outer block pressed against by the outer end of said plunger, an igniter coil on the outer face of said outer block electrically connected at one 50 end to said contact tip and at its other end to said last-named contact shell, and circuit wires respectively electrically connected to said switch and to said first-named contact shell.

JOHN SINKO.
